UNITED STATES PATENT OFFICE

151,317

DESIGN FOR A CHILD'S CHAIR

Donald O. Benson, Racine, Wis., assignor to
Ira Milton Jones, Milwaukee, Wis.

Application November 4, 1946, Serial No. 134,493

Term of patent 14 years

(Cl. D15—8)

To all whom it may concern:

Be it known that I, Donald O. Benson, a citizen of the United States residing at Racine, in the county of Racine and State of Wisconsin, have invented a new, original, and ornamental Design for a Child's Chair, of which the following is a specification, reference being had to the accompanying drawing, forming part thereof.

Figure 1 is a perspective view of a child's chair showing my new design;

Figure 2 is a rear view thereof; and

Figure 3 is a side view thereof.

I claim:

The ornamental design for a child's chair, as shown.

DONALD O. BENSON.
